SLAB MOLDING FRAME

Edwin D. Coddington, Douglaston, Long Island, N. Y., assignor to Reynolds Corporation, New York, N. Y., a corporation of Delaware

Application February 24, 1936, Serial No. 65,480

1 Claim. (Cl. 25—41)

This invention relates to slab molding frames of the type suitable for forming composition floor and wall slabs, or similar prefabricated structural units. The apparatus of the invention is especially suited to the manufacture of that type of floor slab in which the plastic material is applied to a base of heavy paper, or similar sheet material, carrying metallic reinforcing elements which serve to rigidify the finished slab.

10 An important object of the invention is to provide a flat frame or table located at a convenient height above the floor level and serving as a form into which the plastic material composing the slabs is deposited and allowed to harden, one side wall of the form being displaceable clear of the table to allow the convenient removal of the hardened slabs. More particularly this object is accomplished in the preferred form of my invention by mounting the displaceable wall of the 15 form for pivotal movement about an axis located below the plane of the table and providing manually operable means for quickly swinging this wall away from and below the edge of the table so that it offers no obstruction to the removal 20 of the slabs. The displaceable wall is advantageously constructed so as to effect a tight fit with the table top and thus produce a clean even edge upon the finished slab.

Another object of my invention is to provide 25 a slab molding frame especially designed for producing a plurality of floor slabs in a single molding operation, and in which the partition members which divide the table into sections are removable to permit the expeditious cleaning of 30 the form between successive molding operations.

The invention has as other objects to provide a 35 slab molding frame of simple, sturdy and inexpensive construction which occupies the minimum amount of floor space and which includes no complicated mechanism which is apt to get 40 out of order.

Other objects and advantages will be apparent 45 from the following detailed description of a preferred embodiment of the invention, reference being had to the annexed drawings in which:

Figure 1 is a side elevation of a slab molding frame incorporating the novel features of the invention;

Figure 2 is a top plan view of the frame of 50 Fig. 1;

Figure 3 is an enlarged end elevational view of the frame; and

Figure 4 is a detail cross-sectional showing of 55 the top of the frame on the line 4—4 of Fig. 1 and illustrating the manner in which the dis-

placeable wall of the form cooperates with the top.

The slab molding frame disclosed in the drawings comprises a flat horizontal table 1 composed of a pair of channel irons 2 arranged side by side and having downturned flanges 3. The abutting flanges of the channels are welded together as indicated at 4 and this unitary channel assembly is supported adjacent its ends upon legs constituted of upright angle sections 5 arranged in pairs upon opposite sides of the table. Each angle section has one of its flanges secured to the outer flange of the channels 2 while the other outwardly extending flange of the angle provides a flat face for the attachment of the ends of flat truss pieces 6 extending crosswise between the pairs of legs and serving to rigidify the frame. Angle sections 6a extend diagonally downwardly from the sides of the frame and are connected to the legs 5 to afford additional bracing for the same.

Affixed to and extending lengthwise of and adjacent one lateral edge of the table is a bar 7, and located at spaced intervals along the table are removable partition bars 7a, generally similar to bars 7 and having one of their ends snugly fitting within notches 7c formed in the longitudinal bar 7. The bars 7a (in the present case being four in number) are located a distance apart corresponding to the length of the slabs to be molded, and these bars 7a together with the longitudinal bar 7 constitute three side walls of a multiple form designed to receive the plastic material composing the slabs. The fourth side wall of the forms comprises a displaceable bar 9 which is mounted so as to normally project over the longitudinal edge of the table and provided with notches 7d adapted to receive the adjacent ends of the partition bars 7a. Bar 9 serves to close the form, but can be swung outwardly and below the level of the table top to open the form and release the finished slabs. This swinging movement is permitted by the following mechanism:

Secured to and projecting downwardly from the bottom of the channels 2 are a plurality of 45 spaced brackets 10 carrying bearing blocks 11 for a rotatable shaft 12 extending lengthwise of the table a short distance inwardly from that side of the table on which the workman is stationed. The ends of the shaft 12 project beyond the ends 50 of the table and upon each end of the shaft is mounted a bell crank 13 arranged as shown in Fig. 3. This bell crank is constituted of a horizontal arm 13a and an upwardly extending arm 13b which latter is keyed to the shaft 12. A de- 55

pending rod 14 is swivelly suspended upon the outer end of horizontal arm 13a and attached to the bottom of this rod is a counter weight 15, the arrangement being such that this counter-weight tends to swing the arm 13b toward the table.

The outer ends of the two upwardly extending arms 13b at opposite ends of the table are rigidly connected to the square extended ends of displaceable bar 9 and this bar is designed to normally project a slight distance over the longitudinal edge of the table and to abut against the ends of the partition bars 7a. Curved arms 8 disposed at suitable positions along the table are keyed to shaft 12 and affixed to the displaceable bar 9 to afford supplementary support for the latter. A hand lever 17 located intermediate the length of the table is keyed to the shaft 12 and has its end projecting from beneath that side of the table upon which the workman is stationed where it may be conveniently grasped to rock shaft 12 and swing the displaceable bar 9 into the dotted line position indicated in Figs. 3 and 4. For maintaining the form open, a check 17a pivoted upon one of the curved arms 8 may be rocked to engage one of its notched ends with a flange 3 of one of the channels constituting the table top.

In forming slabs of the type which are designed to be keyed together in their assembly into a floor or wall structure it is important that the interfitting edges of the slabs shall be clean and even so as to allow of a tight joint between contiguous slabs. As best shown in Fig. 4, the bars 7 and 9 are cut away so as to produce a complementary overlap and undercut respectively upon opposite longitudinal edges of the slabs, while the partition bars 7a are of rectangular cross-section to impart a straight edge to the ends of the slabs. In order to insure a tight fit between the displaceable bar 9 and the edge of the table, a right-angled notch 16 is formed along the edge of the table to receive the square forward bottom corner of the bar when the frame is closed thus avoiding the formation of a crack into which the plastic material may seep and produce fins upon the edges of the slabs.

In the employment of the slab molding frame just described, the sheet material incorporating the reinforcing elements for the slab is cut to provide a series of blanks which are laid upon the bottoms of the divided sections of the multiple unit form defined by the longitudinal bars 7 and 9 and the partition bars 7a. A portion of such a blank F is indicated in Fig. 2 in place within a form. The plastic material composing the slab,

and being usually of a cementitious character, is deposited within the form sections. After being worked so that it fills out the entire area of the form and effects an anchorage with the reinforcing blanks, the material is smoothed off even with the top of the bars. The slabs are then allowed to remain for a suitable period of time and after hardening are removed from the frame by the workman who rocks the lever 17 to drop the displaceable bar 9 below the table which allows the slabs to be slipped out of the form and off one side of the table.

Preparatory to molding another series of slabs, the table must be cleaned and this is advantageously accomplished by latching down the lever 17 by the check 17a, to hold bar 9 in out-of-the-way position and then removing the partition bars 7a. This allows the loose crumbs of material to be readily swept from the table through the ends and the open side of the form. After cleaning, the partition bars 7a are replaced and the lever 17 is unlatched and the bar 9 restored to closed position with the form, whereupon the apparatus is in readiness for another molding operation.

It will be obvious that various changes may be made in the design and structure of the slab molding frame described above, which is simply exemplary of one embodiment that the invention may assume, without departing from the spirit of my invention.

I claim:

A slab molding frame comprising a horizontal table composed of a plurality of united channel irons having downturned flanges, vertically disposed angle irons connected to the flanges skirt- 35 ing the edge of the table and providing a support for the table, a plurality of vertical wall sections associated with the top of the table and defining therewith a flat open-top form, one of said wall sections being displaceable with reference to the form, said displaceable wall section being provided with an undercut portion upon its molding face, a rotatable shaft extending lengthwise of and beneath the table intermediate its lateral edges, bell cranks fastened to the shaft, one of the arms of the bell cranks being connected to the displaceable wall and the other of the arms of the bell crank being weighted, a notch upon one side of the table adapted to snugly seat a corner of the displaceable wall section, and a crank connected 50 to the shaft for swinging the displaceable wall section away from and below the level of the top of the table.

EDWIN D. CODDINGTON. 55
